Primary Examiner — Clare E Heflin(74) *Attorney, Agent, or Firm* — Stetina, Brunda, Garred and Brucker(57) **CLAIM**

The ornamental design for a light fixture, as shown and described.

DESCRIPTION

FIG. 1 is an upper perspective view of the light fixture of the present invention showing my new design;

FIG. 2 is a lower perspective view thereof;

FIG. 3 is a top view thereof;

FIG. 4 is a front view thereof;

FIG. 5 is a first side view thereof;

FIG. 6 is a second side view thereof opposite that shown in FIG. 5;

FIG. 7 is a rear view thereof; and,

FIG. 8 is a bottom view thereof.

The broken lines in the drawings illustrate features that form no part of the claimed design.
